UNITED STATES PATENT OFFICE.

DAVID F. STOCKBRIDGE, OF OKLAHOMA, OKLAHOMA.

FIREPROOF FLOOR AND CEILING CONSTRUCTION.

1,358,999.

Specification of Letters Patent. Patented Nov. 16, 1920.

Application filed June 12, 1918. Serial No. 239,638.

To all whom it may concern:

Be it known that I, DAVID F. STOCKBRIDGE, a citizen of the United States, residing at Oklahoma, in the county of Oklahoma and State of Oklahoma, have invented a new and useful Fireproof Floor and Ceiling Construction, of which the following is a specification.

This invention relates to a fire-proof floor and ceiling construction, and particularly to a composition block of improved design for use in such construction.

The design of cement floors in fire-proof buildings varies greatly under different conditions of load and use, but, in a great number of cases where the loads are relatively light, the preferred construction comprises a relatively thin cement floor supported at regular intervals by reinforced cement beams or girders formed integral with the floor. These beams are spaced apart in accordance with the conditions in each particular case, the space between the beams being ordinarily between four and ten feet. For factory and warehouse purposes such a floor, with spaced supporting beams integral therewith, is complete when molded and requires no finishing or further attention. In buildings for other purposes, such as store and office buildings, a smooth ceiling beneath the floor is essential.

Such a ceiling may be secured in either one of two ways. First, an expanded metal or other plaster-supporting structure may be extended from beam to beam, and may be so secured to the beams and to the floor above that it will properly support the plaster of the ceiling if applied thereto. The other method of providing a ceiling consists in filling the spaces between the beams with hollow tiles or blocks, to the under sides of which the plaster may be applied.

My present invention relates to the second type of construction, and it is the general object of my invention to provide an improved block for the purpose described, designed to reduce both the weight and cost of such construction and to increase the strength and reliability of the resulting structure.

With this general object in view, an important feature of my invention consists in the provision of a series of composition

blocks having intersupporting elements, whereby the stronger portion of each block is effective to support the weaker portion of the next adjacent block, thus providing a complete structure of uniform and sufficient strength.

In the preferred form of my invention each block is made with one open side, the other side being closed and having a projection thereon adapted to engage the next adjacent block on its open side, and to partially support said block.

Other features of my invention relate to arrangements and combinations of parts which will be hereinafter described and more particularly pointed out in the appended claims.

Preferred forms of my invention are shown in the drawings, in which—

Figure 1 is a vertical sectional view of a fire-proof floor and ceiling taken transversely of the beams and lengthwise of my improved block;

Fig. 2 is a detail perspective view taken substantially from the plane of the line 2—2 in Fig. 1;

Fig. 3 is a partial perspective view looking in the direction of the arrow 3 in Fig. 7;

Fig. 4 is a partial perspective view taken from the plane of the line 4—4 in Fig. 7;

Fig. 5 is a side view of my improved block;

Fig. 6 is a partial plan view thereof;

Fig. 7 is a perspective view of the whole block looking in the direction of the arrow 7 in Fig. 6, and

Fig. 8 is a sectional view of a slightly modified floor structure.

Referring to Fig. 1, I have shown a section of a fire-proof floor and ceiling comprising a cement floor 10 supported by spaced integral cement beams 11 and 12 reinforced by metal rods 13. Between the beams I have indicated in section my improved hollow blocks 14. The preferred construction of these blocks is shown in Figs. 2 to 7 inclusive, each block comprising a top 15, a bottom 16, ends 17 and 18, and a closed side 19 upon which is formed a rib or projection 20. The top of the block is shown herein as having an arched section, and the rib 20 corresponds in shape to the section of the top 15, having its upper edge substantially in line with the lower face of

the top 15. The ends of the rib 20 are also substantially in line with the inner faces of the ends 17 and 18 of the block 14. These ends 17 and 18 are preferably grooved or 5 roughened so that the blocks may be securely supported by their engagement with the cement beams at each end, and the lower edge or corner of each end of the block is preferably provided with a dove-tailed recess 21 for a purpose to be described. 10

These blocks may be made of cement or of any other suitable material or composition and may, if desired, be reinforced as indicated in Figs. 5 and 6 by embedding 15 metallic mesh fabric 22 in the top 15 and by placing reinforcing wires or rods 23 and 24 in the closed side 19. Similar rods 24 may, if desired, be extended across the bottom 16.

Having described the details of construction of my improved composition block, the use and advantages thereof will be apparent.

Each block extends across the entire space from beam to beam, and a sufficient number 25 of blocks will be placed in succession to extend the length of the beams. When the blocks are thus in adjacent position, it will be seen that the open or unsupported edge of the top 15 of each block rests upon the 30 rib or projection 20 upon the reinforced closed side of the next adjacent block. The top of each block is thus firmly supported along one edge by its own closed side, and along the opposite edge by the closed side 35 of the next adjacent block, the successive blocks being thus intersupported.

The ends of the ribs 20 are cut away just 40 enough so that the rib will fit within the end walls of the next adjacent block and the rib therefore serves also to prevent relative lateral displacement of the blocks. The recesses 21 in the lower end corners of the blocks are adapted to receive and position the planks or forms F upon which the 45 blocks are supported prior to the pouring of the cement to make the beams and floor. After the cement has set, the forms F are removed and the under side of the blocks and beams may be plastered, as indicated at 50 30 in Fig. 1, the plaster along the under side of the beam being securely retained by the dove-tailed recesses.

In Fig. 8 I have indicated a slight modification in which the recesses 21 are omitted 55 and the under faces of the blocks rest directly upon the forms F. With this construction the under sides of the beams and blocks form a continuous smooth surface which may be left unfinished, or which may be plastered as indicated at 31.

The block at one end of each series of blocks will necessarily have its open side outermost, and this open side should be closed in some convenient manner before 60 the block is placed in position. Such clo-

sure is conveniently accomplished by placing the block with its open side downward in a shallow pool of cement and allowing a sufficient thickness of cement to harden within the block before it is removed. Any 70 other convenient method of closing the open side may be utilized.

While I have shown my improved blocks as embodied in constructions in which they are covered by a cement floor layer, they 75 may also be used in constructions in which the floor layer is omitted, as in cases where the space above the ceiling is merely an unfinished loft. The blocks themselves are of sufficient strength to sustain any incidental 80 load encountered in such situations.

Having fully described my invention, it will be seen that I have provided an exceedingly strong and rigid construction while at the same time I have greatly reduced the 85 weight by providing each block with an open side extending the whole length thereof. Furthermore, by utilizing the intersupporting feature I have been enabled to reduce the weight without in any way impairing 90 the strength or reliability of the block.

Having described my invention, it will be evident that other changes and modifications can be made therein by those skilled in the art without departing from the spirit 95 and scope thereof as set forth in the claims, and I do not wish to be otherwise limited to the details herein disclosed, but what I claim is—

1. A hollow composition block for use in 100 fire-proof floor and ceiling construction formed as a single piece of material with top, bottom, two ends, and one side integral and substantially closed, and with the remaining side open, said closed side having 105 a portion effective to engage and support the top of the next adjacent block along the open side of said block, said blocks being of substantially greater width than height, and being of relatively short length 110 and all of the walls thereof being relatively thin and of substantially uniform thickness throughout the structure of the block.

2. A hollow composition block for use in 115 fire-proof floor and ceiling construction formed as a single piece of material with top, bottom, two ends, and one side integral and substantially closed, and with the remaining side open, said block having an outwardly projecting rib on its closed side 120 spaced from the top and effective to extend beneath and support the top of a similar adjacent block along the open side of said block, the ends of said rib being also spaced from the end of the block and being effective to prevent relative lateral displacement of adjacent blocks.

3. A hollow composition block for use in 130 fire-proof floors and ceiling construction formed as a single piece of material with

top, bottom, two ends, and one side integral and substantially closed, and with the remaining side open, said closed side having a portion effective to support the top of the next adjacent block along the open side of said block and the top of said block being of substantially uniform thickness through-

out and being substantially in the shape of a flattened longitudinal arch, whereby its strength is increased.

10

In testimony whereof I have hereunto affixed my signature.

DAVID F. STOCKBRIDGE.
